(57) **CLAIM**

The ornamental design for a mask for a cabinet door opening, as shown and described.

DESCRIPTION

FIG. 1 is a perspective view of a mask for cabinet door opening in use condition.

FIG. 2 is a front elevational view of the mask for cabinet door opening.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.

The broken line showing of a portion of a rear of the mask for cabinet door opening forms no part of the claimed design. The broken line showing of a cabinet door illustrates the environment of the claimed design and forms no part thereof.
